United States Patent Office

Des. 177,653
Patented May 8, 1956

177,653

BAND WELDER

Dorsey B. Thomas, Savannah, Ga.

Application July 26, 1955, Serial No. 37,136

Term of patent 14 years

(Cl. D26—1)

Fig. 1.

Fig. 2.

Fig. 3.

Figure 1 is a front perspective view of a band welder showing my new design;

Figure 2 is a side perspective view taken from the side of Figure 1; and,

Figure 3 is a front elevational view thereof.

I claim:

The ornamental design for a band welder, as shown.
